US00D691947S

(12) **United States Design Patent**
Cole et al.

(10) **Patent No.:** **US D691,947 S**
(45) **Date of Patent:** **** Oct. 22, 2013**

(54) **SKIN CLEARING AND TONING DEVICE
CHARGING CRADLE**

(71) Applicant: **Carol Cole Company**, Carlsbad, CA (US)

(72) Inventors: **Carol Cole**, Carlsbad, CA (US); **Tera Valdez**, Carlsbad, CA (US)

(73) Assignee: **Carol Cole Company**, Carlsbad, CA (US)

(**) Term: **14 Years**

(21) Appl. No.: **29/448,264**

(22) Filed: **Mar. 11, 2013**

Related U.S. Application Data

(63) Continuation of application No. 29/419,763, filed on May 1, 2012, now Pat. No. Des. 677,622.

(57) **CLAIM**

The ornamental design for a skin clearing and toning device charging cradle, as shown and described.

DESCRIPTION

FIG. 1 is a perspective view of the skin clearing and toning device charging cradle of the present invention;

FIG. 2 is a front elevational view of the skin clearing and toning device charging cradle shown in FIG. 1;

FIG. 3 is a rear elevational view of the skin clearing and toning device charging cradle shown in FIG. 1;

FIG. 4 is a left side elevational view of the skin clearing and toning device charging cradle shown in FIG. 1, the right side view being a mirror image of the illustrated view;

FIG. 5 is a top plan view of the skin clearing and toning device charging cradle shown in FIG. 1; and,

FIG. 6 is a bottom plan view of the skin clearing and toning device charging cradle shown in FIG. 1.

The broken lines shown in the drawings are included for the purpose of illustrating environmental structure and form no part of the claimed design.

1 Claim, 4 Drawing Sheets
